ADJUSTABLE DOORSTOP

Russell J. Wallen, Minneapolis, Minn.

Application February 27, 1952, Serial No. 273,617

4 Claims. (Cl. 16—49)

1

My invention relates to improvements in door stops and, more particularly, to adjustable door stops.

An object of this invention is to provide an extremely simple and highly efficient door stop having a removable pintle and applicable to any one of the hinges of a casement window.

A further object is to provide a novel door stop that is readily adjustable to stop a door in any desired open position.

Other objects of the invention will be apparent from the following description, reference being had to the drawing.

To the above end, the invention consists of the devices and combination of devices hereinafter described and defined in the claims.

In the accompanying drawing, which illustrates one embodiment of the invention, like characters indicate like parts throughout the several views.

Referring to the drawing:

Fig. 1 is a plan view of the improved door stop applied to a hinge attaching a door to a door frame in a door opening in a wall structure, said door and wall structure being fragmentarily shown in section;

Fig. 2 is an elevational view of the parts shown in Fig. 1;

Fig. 3 is a view corresponding to Fig. 1, except it is somewhat more fragmentary with the door "stopped" in an open position by the novel door stop;

Fig. 4 is a plan view of the door stop, partly in plan and partly in section, removed from the hinge; and

Fig. 5 is an elevational view of one of the stop pins.

For the purpose of showing the novel door stop applied to stop the opening of a door, there is shown fragmentarily in the drawing a wall structure including studs 5 to which is applied, at a door opening, lath and plaster or a wall board 6, a door frame 7 in the door opening and having a door stop 8, and a door 9 attached by hinges 10, only one of which is shown, to the door frame 7. One of the upright members 11 of a casing is secured to the door frame 7 and wall structure 5—6. The hinge 10 has a removable pintle 12 provided with a head 13 that limits the endwise movement of said pintle into the aligned holes in the interlocked lugs 14 of the leaves of hinge 10.

Referring now in detail to the improved door stop which includes a pair of wings 15 and 16 pivotally connected by a hollow rivet 17, the inter-

nal diameter of which is approximately the same as the aligned holes in the hinge lugs 14, the pivotally connected end portions of the wings 15 and 16 are inwardly offset, respectively. Integral with the outer end portions of each wing 15—16 is a pressure plate 18 and 19, respectively. These pressure plates 18—19 depend from the inner longitudinal edge portions of the wings 15—16 and are offset therefrom. Each wing 15—16 and its pressure plate 18—19 is formed of a single piece of flat metal.

The improved door stop further includes a spring 20 formed of a single piece of wire having at its longitudinal center a coil that affords an eye 21 of substantially the same diameter as the rivet 17.

To attach the improved door stop to the hinge 10, the pintle 12 is removed from the hinge lugs 14, by lifting, and inserted endwise through the hollow rivet 17 and the eye 21 in the spring 20 with the end portions of said spring overlapping the pressure plates 18—19 on their outer faces.

The pintle 12 is next replaced in the hinge lugs 14 with wing 15 extending transversely of the door 9 and wing 16 extending transversely of the casing 11. The spring 20 is under strain to hold the wing 15 with its pressure plate pressed against the door 9, and also holds the wing 16, with its pressure plate 19 pressed against the casing 11. The offset pressure plates 18—19 prevent the wings 15—16 from coming in contact with door 9 and the casing 11. With the pintle 12 replaced in the hinge lugs 14, the spring 20 and the rivet 17 are held between the uppermost hinge lug 14 and the head 13 of the pintle 12.

The improved door stop further includes a depending stop pin 22 on the wing 16 that is engaged by the wing 15 during the opening of the door 9 to stop the same in a predetermined open position. The stop pin 22 has a screw-threaded upper end portion 23, of reduced diameter, insertable in any one of a plurality of longitudinally spaced holes 24 in the wing 16 with which it has threaded engagement. Obviously, by inserting the stop pin 22 in any one of the holes 24, the opening of the door 9 may be stopped in a multiplicity of different open positions.

To secure a closer adjustment of the door stop from that obtained by shifting the stop pin 22 in the holes 24, stop pins of different diameters may be used. One of these stop pins is shown in Fig. 5 and designated by the numeral 25.

From the above description and the accompanying drawing, it is evident that the improved

door stop is capable of modifications as to construction and arrangement of parts.

What I claim is:

1. A stop of the class described, including a pair of wings having overlapping portions provided with aligned holes through which the pintle of a hinge attaching a door to a support may be inserted, said wings being constructed and arranged the one to engage the support as a base of resistance and the other wing being held for movement with the door, and stop means for limiting the movement of the last noted wing by the opening of the door to stop said door in a predetermined open position, said stop means being adjustable to vary the stopped open position of the door.

2. A stop of the class described, including a pair of wings having overlapping portions provided with aligned holes through which the pintle of a hinge attaching a door to a support may be inserted, said wings being constructed and arranged, the one to engage the support as a base of resistance and the other wing to overlap the door and be engaged thereby, spring means, which is normally under strain to move the last-noted wing toward the door to be engaged thereby during the opening of the door and moved therewith, and stop means for limiting the movement of the last noted wing by the opening of the door to stop said door in a predetermined open position, said stop means being a pin attached to the first noted wing and extending in the path of movement of the last noted wing.

3. A stop of the class described, including a pair of wings having overlapping portions provided with aligned holes through which the pintle of a hinge attaching a door to a support may be inserted, said wings being constructed and arranged, the one to engage the support as a base of resistance and the other wing to overlap the door and be engaged thereby, spring means,

which is normally under strain to move the last noted wing toward the door to be engaged thereby during the opening of the door and moved therewith, one of the wings having a row of longitudinally spaced holes, and stop means held in any one of said holes to be engaged by the other wing during the opening of the door and stop the same.

4. A stop of the class described, including a pair of wings, a tubular rivet pivotally connecting the wings and through which rivet the pintle of a hinge attaching a door to a support may be inserted, each wing having on its outer end portion an upright pressure plate, one of which is constructed and arranged to engage said support as a base of resistance and the other wing being constructed and arranged to be engaged by the door during its opening movement and be moved therewith, a spring wire coiled at its intermediate portion to provide an eye through which said pintle may be inserted with the end portions of said spring wire bearing on the pressure plates and normally under strain to move one of the wings toward the support and the other toward the door, the wing having the pressure plate engageable with the support being provided with a row of longitudinally spaced holes, and a stop pin insertable in any one of the holes and having screw-threaded engagement with said wing, said stop pin being in the path of movement of the other wing to stop the opening of the door.

RUSSELL J. WALLEN.
